DESIGN FOR A FOOT INVIGORATOR

John K. Milton, Chicago, Ill.

Application January 22, 1941, Serial No. 98,273

Term of patent 14 years

To all whom it may concern:

Be it known that I, John K. Milton, a citizen of the United States, residing at Chicago, in the county of Cook and State of Illinois, have invented a new, original, and ornamental Design for Foot Invigorators, of which the following is a specification, reference being had to the accompanying drawing, forming part thereof.

Fig. 1 is a perspective top view of a foot invigorator, showing my new design; and

Fig. 2 is a perspective bottom view thereof.

I claim:

The ornamental design for a foot invigorator, as shown.

JOHN K. MILTON.
